(57) **CLAIM**

The ornamental design for a treatment tool for endoscope, as shown and described.

DESCRIPTION

FIG. 1 is a front, top and left-side perspective view of the treatment tool for endoscope;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is an enlarged view of the area 8 indicated by the two dot-dash broken lines in FIG. 5; and,

FIG. 9 is an enlarged view of area 9 indicated by the two dot-dash broken lines indicia in FIG. 6.

The broken lines depict parts of the treatment tool for endoscope that form no part of the claimed design. The dot-dash chain lines depict enlargement areas, and thus form no part of the claimed design.
